WATER HEATER CONTROL

Harry R. Greene, Pasadena, Calif., assignor to General Controls Co., Glendale, Calif., a corporation of California

Application April 15, 1959, Serial No. 55,528

Term of patent 14 years

(Cl. D26—13)

Figure 1 is a front elevational view of the water heater control, showing my new design;

Figure 2 is a left side elevational view thereof;

Figure 3 is a right side elevational view thereof;

Figure 4 is a rear elevational view thereof;

Figure 5 is a top plan view thereof; and

Figure 6 is a bottom plan view thereof.

The dominant features of my design are shown in solid lines.

I claim:

The ornamental design for a water heater control, as shown and described.
